JAMES W. SMITH AND JOHN P. SMITH, OF ELDER'S RIDGE, PENNSYLVANIA.

Letters Patent No. 73,935, dated January 28, 1868.

IMPROVED CAR-COUPLING.

The Schedule referred to in these Letters Patent and making part of the same.

TO ALL WHOM IT MAY CONCERN:

Be it known that we, JAMES W. SMITH and JOHN P. SMITH, of Elder's Ridge, Indiana county, in the State of Pennsylvania, have invented certain new and useful Improvements in Car-Coupling; and we do hereby declare that the following is a full, clear, and exact description of the same, reference being had to the annexed drawings, and to the letters of reference marked thereon, making part of this specification, in which—

Figure 1 is a side view.

Figure 2 is an end view.

Figure 3 is a view of the draw-head detached from the car.

Figure 4 is a bottom view of the same.

Figure 5 is an end sectional view of the draw-head, showing its bevelled bearings.

My invention consists in a simple and practical method of coupling and uncoupling cars by means of a foot-rod or lever, which is connected by a chain with the coupling-pin or bolt. The chain works in a friction-roller, having its bearings in a standard or upright, secured to the draw-head in front of the foot-rod, and immediately in the rear of the opening through which passes the coupling-pin, so that when the foot-rod is depressed the chain drawing on the coupling-pin elevates sufficiently to allow of the free passage of the shackle or link under the same. By means of a slotted guide-plate, attached to the platform of the car, and an opening in the rear of the draw-head, the foot-rod or lever is compelled to always occupy a perpendicular position, and to work in a line exactly parallel with the coupling-pin or bolt after the latter has entered the draw-head. The rod or lever can readily be depressed by the foot, but only remains in that position so long as the pressure is retained upon the same, for the instant the pressure is withdrawn a spring, attached to the lower end of the rod or lever, and which has its bearing underneath the car, forces the rod back to its former position.

My invention also consists in attaching the draw-head to the car by means of bevelled bearing-plates, a portion of the under side of the draw-head being bevelled in a like degree, so that it may work freely in the plates. The bevel on the draw-head only extends a proper distance to allow of the draw-head's receding sufficiently far when the cars strike to break the force and violent jar caused by the sudden concussion.

In view of the numerous serious and fatal accidents that have occurred to railroad employes by being jammed between the cars, while in the act of coupling or uncoupling the same, numberless inventions have been patented, the aim of which has been to furnish a secure coupling, and one which at the same time could be operated with less difficulty, and in a degree, at least, lessen the danger which is incident to the working of the coupling now in general use. Many reasons might be assigned why scarcely any of the patented couplings have never been introduced. In the first place, they are too expensive; in the second place, they are too complicated; and again, they do not possess the requisite strength.

My invention has, to recommend it, its cheapness, its simplicity, and its efficiency. The expense of applying it to the coupling now in use is exceedingly trifling, requiring no alteration in the car itself, and scarcely any in the draw-head. There is no complicated mechanism to become disarranged, and the entire draught is borne, as in the old plan, directly by the coupling-pin.

To enable others skilled in the art to make and use my invention, I will proceed to describe its construction and operation.

A is the draw-head, which is constructed in the usual manner, and furnished with the mouth A', of the ordinary form. B is a boss, immediately in the rear of the mouth A', and through which the coupling-pin b passes. To the under side of the car C there are rigidly secured two heavy guide-plates, D D. These plates are bevelled, as already shown in figs. 4 and 5, and furnish bearings for the draw-head A, which works freely in the plates D D, the bevelled face allowing sufficient play, so that when the cars come in contact, the draw-heads will slightly yield, thus breaking the force of the concussion. Immediately in the rear of the boss B there is firmly secured a standard or upright, a'. In a slot in the upper portion of this standard or upright, a', there is pivoted a grooved friction-roller, b'. In the groove of the roller b' works a short chain, a¹, which is attached at one end to the head of the coupling-pin b, and at the other to the foot-rod a. The foot-rod a is retained in an elevated position by means of the spring c, which has its bearing in a line, e, attached to the bottom of the car. This spring c passes through an eye, c', in the lower portion of the foot-rod or lever a.

The operation is as follows: Let us suppose the cars are connected together by the ordinary shackle or link in general use, and it is desired to uncouple the same; place the foot on the rod or lever α , depress the same; this will draw the chain α^1 over the friction-pulley b^1 , which, being attached to the coupling-pin b , will gradually elevate the same to a position which will allow of the free exit of the link or shackle, which, when effected, the foot can be removed, and the spring c will immediately return the lever α to its normal position.

Having thus described our invention, what we claim as new therein, and desire to secure by Letters Patent of the United States, is—

The spring c , in combination with the lever and foot-rod α , upright α^2 , and chain α^1 , and coupling-pin b , when the same are so arranged as to operate substantially as described, and for the purpose set forth.

In testimony whereof, we have signed our name to this specification in the presence of two subscribing witnesses.

JAMES W. SMITH,
JOHN P. SMITH.
